UNITED STATES PATENT OFFICE.

FREDERICK L. MCGAHAN, OF LOS ANGELES, CALIFORNIA; VIOLA E. WALKER
ADMINISTRATRIX OF SAID FREDERICK L. MCGAHAN, DECEASED.

METHOD OF TREATING AND HANDLING PRODUCTS OF COMBUSTION.

1,398,734.

Specification of Letters Patent.

Patented Nov. 29, 1921.

Application filed July 5, 1917. Serial No. 178,802.

To all whom it may concern:

Be it known that I, FREDERICK L. MCGAHAN, a citizen of the United States, residing at Los Angeles, in the county of Los Angeles and State of California, have invented a new and useful Method of Treating and Handling Products of Combustion, of which the following is a specification.

My invention relates to a method of conducting and consuming products of combustion, such as smoke, stack gases and fumes from fuel burning devices throughout a city, or any section thereof. My method is carried out in a system adapted to collect the smoke, stack gases and fumes from fuel burning devices in all or any number of the buildings in a city that are now released into the atmosphere in great clouds through the stacks and chimneys of the various buildings, such as manufacturing plants, office buildings, residences, etc., conduct the products of combustion to a central consuming station where they may be compounded into valuable by-products at such station, thereby obviating the necessity of the usual stacks and chimneys for conveying the smoke, from the fuel burning devices, and thus absolutely abate the smoke nuisance in cities equipped with such system.

It is, therefore, an object of my present invention to conduct the products of combustion, such as smoke, stack gases and fumes directly from fuel burning devices in any number of buildings, in a circuit or district to a suitable station pneumatically, by means of a suitable draft producer, and to continuously deposit or feed the products of combustion into a suitable smoke condensing mechanism, and therein compounding the products of combustion into valuable by-products, such as paint pigment or other by-products.

With the above and other objects in view, as will appear hereinafter, reference is had to the accompanying drawings illustrating the steps of the method and one form of an apparatus for carrying the method out, said drawings forming a part of this specification wherein like characters of reference denote similar parts throughout the several views:

Figure 1, is a diagrammatic plan view of my smoke conducting, consuming and compounding system.

Fig. 2, is a sectional elevation of a build-

ing equipped with a suitable smoke condenser and vacuum draft producer and showing the main service pipe leading therefrom.

Fig. 3, is a sectional elevation of a part 60 of two buildings upon opposite sides of a street, clearly showing that the smoke conveying service pipe passes under the buildings and crosses the street in a manner so as not to interfere with the usual sewer, water, 65 or other system.

Fig. 4, is a sectional view of a building showing the installation of the branch conduits, or leads into a building and their relation to the usual water and sewer pipes. 70

Referring to the accompanying drawings, I have shown in Fig. 2, a suitable building 1. Within the building 1, which will be known hereinafter as a district or central treating station, I propose to install the necessary 75 equipment for transmitting the smoke, stack gases and fumes from the fuel burning devices, of one, or many buildings and from any distance to a suitable condenser wherein the smoke, stack gases and fumes may be 80 converted into valuable by-products, in paint pigment, or other form.

The apparatus or equipment for conducting or conveying the products of combustion from fuel burning devices, located in any 85 number of buildings within the capacity of the central station, comprises a suitable vacuum draft producer 2, adapted to be actuated by means of any suitable power, such for instance, as a motor 3, through the 90 medium of a belt 4, or its equivalent.

Leading from the vacuum draft producer 2, is a pipe 5, having suitable connection, such as at 6, with the main vacuum draft and smoke transmission service pipe, or 95 main 7, leading in as many ways as desirable from pipe 5.

One of the service pipes 7, is shown as leading off to the left, and the other is shown as leading off to the right, and by placing 100 Fig. 3, of the drawings, to the right of Fig. 2, of the drawings, it will be seen that the main service pipe 7, is adapted to pass through the building 8, and cross the street 9, without interfering with the usual city 105 sewer pipes 10, or the usual city water pipes 11.

This main service pipe 7, it will be further observed, by placing the drawing Fig. 4, to the right of drawing Fig. 3, may continue 110

through building 12, at any convenient place, preferably through the cellar or basement, below the floor level, as in the previously mentioned buildings. This main service pipe 7, may extend any suitable distance that the vacuum draft producer 2 may be capable of drawing or sucking the smoke to the central consuming station.

Suitable couplings 13, as shown in Fig. 3, 10 may be employed for connecting the main service pipe at desired intervals. Referring to Figs. 1, 3 and 4, it will be observed, that the various fuel burning devices, which, for convenience, have all been designated with 15 the same reference numeral 14, have suitable connection, as at 15, with the main service pipe 7, through the medium of suitable branch pipes, or leads 16, each of which is provided adjacent the fuel burning device 20 with a suitable regulating device, or draft damper 17.

Hollow catch basins to form relay chambers are used in connection with my system, and one of these basins 18, is preferably connected with the main service pipe 7, in each 25 building A, which buildings are illustrated in dotted lines in the plat plan shown in Fig. 1. One or more of these basins 18, may also be placed in the station 1. Surrounding 30 each one of the catch basins 18, is a suitable steam pipe 19, leading from a suitable source of steam supply, such as a boiler 20, shown in the drawings as located at the station 1. The object of the steam pipe is to keep the 35 interior of the basins warm so that the heavier products of combustion, collected therein may be drained off instead of clogging the service pipe 7. The catch basins 18, are adapted to concentrate the heavier particles of tar from smoke, also the catch 40 basins form relay vacuum chambers, such as are commonly found in pumps forming a means for equalizing the vacuum through the pipe system.

45 The smoke, stack gases and fumes sucked or conveyed to the station 1, by means of the vacuum draft producer 2, are delivered directly from the vacuum draft producer to a suitable smoke, gas and fume condensing 50 means 21, which means may be of any suitable construction. The products of combustion are adapted to be deposited in the condensing means from throughout the entire pipe system to be condensed and compound- 55 ed into valuable by-products, such for instance, as products in the form of paint pigment. The by-products in the paint pigment, or other form, may be drained off from the condenser 21, and into a suitable container 60 or its equivalent 22. A suitable water pipe 23, is connected with the condenser 21, for furnishing water thereto, when desired, from any suitable source.

The reference character 24, designates a 65 suitable pumping means, by means of which

water may be pumped into a suitable reservoir or tank 25. Water within the tank 25, may be conveyed to the boiler through the pipe connection 26.

The system for carrying out the present 70 method is operated, as is manifest, pneumatically, under a maintained vacuum draft throughout the entire pipe system which may cover many blocks in a system, or, if desired, may cover but a single building, 75 such for instance, as a large manufacturing plant, office building, or like place, where it would pay to install the system. The apparatus in the station 1, is automatic to take care of all possible contingencies throughout the entire pipe system.

As illustrated in dotted lines designated 27, in the plat plan shown in Fig. 1, the main service pipe 7, extends down the alley 28, to which may be connected the branch 80 pipes 14, in any well-known manner. Further, the main service pipe 7, may extend under sidewalks 29, as shown in dotted lines designated 30, and to which the branch pipes 14, may be connected in any well-known and 90 usual manner. And still further, the main service pipe may be laid into the streets 31, if so desired, as is manifest. The exact place or location of the main service pipe or pipes is an immaterial feature, as the 95 branch pipes 14, may be connected thereto from whatever point the fuel burning device, or devices, may be located.

For convenience of illustration only, the main service pipes 7, have been shown in the 100 drawings, in full lines, as running directly under the houses or buildings, which buildings have been illustrated by dotted lines in Fig. 1, and in full lines in the remaining views.

The essential feature of my present invention is to conduct, pneumatically, the smoke, fuel gases and fumes from any number of fuel burning devices to a by-products manufacturing station, at which place the 110 smoke, stack gases and fumes, may be deposited into suitable condensing mechanism, for conversion into its various constituents.

My improved method for treating smoke from stoves, furnaces, boilers, etc., it will 115 be readily understood, will absolutely abate the terrible smoke nuisances of our cities leaving the atmosphere pure and clean.

I claim:

1. The method of recovering coal tar and 120 other by-products from smoke fumes discharged from fuel burning devices, which method consists in conducting the smoke fumes discharged from a plurality of fuel burning devices to a treating station; trapping, concentrating or reducing certain constituents of the smoke fumes at intervals between the fuel burning devices and the treating station; heating said trapped, concentrated or reduced constituents so that 125

they may pass out of the system, and finally subjecting the remainder of the fumes to treatment at said station to further separate condensable elements from said fumes.

- 5 2. The method of recovering coal tar and other by-products from smoke fumes discharged from fuel burning devices, which method consists in conducting the smoke fumes discharged from a plurality of fuel burning devices to a treating station by suction vacuum draft located at said station; equalizing the vacuum at intervals between the fuel burning devices and the treating station; trapping, concentrating or reducing certain constituents of the smoke fumes at intervals between the fuel burning devices and the treating station; and finally subjecting the remainder of the fumes to treatment at said station to further separate condensable elements from said fumes.
- 10 20 3. The method of recovering coal tar and

other by-products from smoke fumes discharged from fuel burning devices, which method consists in conducting the smoke fumes discharged from a plurality of fuel burning devices to a treating station by suction vacuum draft located at said station; equalizing the vacuum at intervals between the fuel burning devices and the treating station; trapping, concentrating or reducing certain constituents of the smoke fumes at intervals between the fuel burning devices and the treating station; heating said trapped, concentrated or reduced constituents so that they may pass out of the system, and finally subjecting the remainder of the fumes to treatment at said station to further separate condensable elements from said fumes.

In testimony whereof, I have hereunto signed my name to the specification.

FREDERICK L. McGAHAN.
